US00D787490S

(12) **United States Design Patent** (10) Patent No.: **US D787,490 S**
(45) Date of Patent: ** *May 23, 2017

(54) **CASE FOR MOBILE COMMUNICATIONS DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Danielle De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **APPLE INC.**, Cupertino, CA (US)

(*) Notice: This patent is subject to a terminal disclaimer.

(**) Term: **14 Years**

(21) Appl. No.: **29/492,404**

(22) Filed: **May 30, 2014**

(57) **CLAIM**

The ornamental design for a case for mobile communications device, as shown and described.

DESCRIPTION

FIG. 1 is a bottom front perspective view of a case for mobile communications device showing our new design; FIG. 2 is a bottom rear perspective view thereof; FIG. 3 is a top rear perspective view thereof; FIG. 4 is a top front perspective view thereof; FIG. 5 is a front view thereof; FIG. 6 is a top view thereof; FIG. 7 is a bottom view thereof; FIG. 8 is left side view thereof; and, FIG. 9 is a right side view thereof.

(Continued)

The solid line that forms the innermost edge of the front of the case and the solid line that forms the innermost edge of the rear of the case are boundaries of the claimed design and are part of the claimed design. All surfaces on the interior of the case that are between these two solid line boundaries form no part of the claimed design. The broken lines on the exterior of the case that represent through holes are boundaries of the claimed design and form no part of the claimed design. All other broken lines on the exterior and interior of the case depict environmental subject matter that forms no part of the claimed design.

1 Claim, 7 Drawing Sheets
